US00D922547S

(12) **United States Design Patent** (10) **Patent No.:** **US D922,547 S**
(45) **Date of Patent:** **** Jun. 15, 2021**

(54) **SEAL MEMBERS FOR USE IN SEMICONDUCTOR PRODUCTION APPARATUSES**

(71) Applicant: **Valqua, Ltd.**, Tokyo (JP)

(72) Inventors: **Sangho Kim**, Pyeongtaek-si (KR); **Nobuhiro Yoshida**, Gojo (JP)

(73) Assignee: **Valqua, Ltd.**, Tokyo (JP)

(**) Term: **15 Years**

(21) Appl. No.: **29/715,089**

(22) Filed: **Nov. 27, 2019**

(57) **CLAIM**

The ornamental design for a seal member for use in semiconductor production apparatuses, as shown and described.

DESCRIPTION

FIG. 1 is a perspective view of a seal member for use in semiconductor production apparatuses, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a cross-sectional view thereof; and,

FIG. 9 is an enlarged cross-sectional view of a portion thereof.
